UNITED STATES PATENT OFFICE.

HERBERT HENRY BERRY AND WILLIAM J. MARKHAM, OF LONDON, ENGLAND.

PROTECTED OR ARMOR-CLAD ELECTRIC-SWITCH FUSE.

970,296.

Specification of Letters Patent. Patented Sept. 13, 1910.

Application filed June 9, 1910. Serial No. 566,067.

To all whom it may concern:

Be it known that we, HERBERT HENRY BERRY and WILLIAM JAMES MARKHAM, both citizens of the United Kingdom of Great Britain and Ireland, and residents of 78 Upper Thames street, London, E. C., England, have invented certain new and useful Improvements in Protected or Armor-Clad Electric-Switch Fuses, of which the following is a specification, such as will enable others skilled in the art to which it appertains to make and use the same.

This invention relates to electric switches and electric switch fuses of that type which are inclosed in a metal case having a hinged cover which carries the switch blades, the said blades being fixed to a rod adapted to move to and fro through or below the said cover and being mounted thereon, the said switch blades and the rod with their connecting parts being spring controlled for the purpose of producing the necessary quick make and quick break movements. Forms of this switch have been devised in which it is impossible to close the cover with the switch blades in the "on" position and also impossible to open the cover when the blades are in that position it being necessary to withdraw the blades to the "off" position to both close and open the cover and our invention is applicable to this form of switch. Hitherto the requisite movements of the switch blades from the "on" to the "off" positions and vice versa have been accomplished by attaching to the outer end of the rod a knob or equivalent by which it can be pulled out and thrust back and although this arrangement answers its purpose well when there is plenty of room in the place where the switches are fixed it is unsuitable in those places where the space is limited and access to the knob not easily possible.

To make the class of switch first herein referred to more convenient in use and particularly to overcome the objection mentioned in the last paragraph we have devised a means whereby the movements of the rod carrying the switch blades can be effected without inconvenience and the switch can be fixed in more limited space than where the knob or other such handle is provided.

Our invention consists in providing a hand lever at either side of the case containing the switch to which hand lever a lever inside

the case is connected, the said lever being adapted to push on and pull off the switch blades according to the direction in which the hand lever is moved.

We will now describe our invention with reference to the accompanying drawings in which—

Figure 1. is a sectional view of a combined double pole switch and fuses with its hinged cover open. Fig. 2. is a sectional view showing the hinged cover closed with the switch and fuses in its "current off" position. Fig. 3. is a sectional view showing the hinged cover closed and the switch and fuses in its "on" position. Fig. 4. is a sectional view showing that it is impossible for a careless operator to close the same if the switch and fuses are in the "on" position. It also shows that the position of the switch contacts must be in the "off" position, and the cover closed as in Fig. 2 before the switch can be placed in "on" position as in Fig. 3. Figs. 1, 2, 3 and 4 show an outer case A with a lid or cover B arranged to open upon a hinge C. Attached to the cover a rapid make and rapid break switching device is arranged to travel backward and forward in a parallel direction between two fixed points.

In the present example a band spring D rigidly fixed to the cover B at E, E', has two loose members or metal plates 2, 2', sprung into slots in the spring D at H, H', and into V-shaped grooves in a plunger head 3 which is attached to a coupling or couplings or plunger or plungers carrying the switch blades and the inter-locking projecting tube N'. Formerly the plunger or plungers to which the switch mechanism is coupled has been guided through an aperture or apertures in the cover of the case but in our improved apparatus we arrange the switch coupling or mechanism to slide backward and forward between two fixed points on one, two or more guide rods M which we attach to the inside cover of the case. In order to obtain the make and break action of the switching device we arrange one or more operating levers F fixed to a spindle G the said spindle taking its bearings on opposite sides of the case A, one end of the spindle G is arranged to project through a gland I in the side of the case and has a fixed or detachable lever or key P for the purpose of moving the levers F and of op-

erating the switch. The lever F is a bifurcation F' in its free end, engaging a pin 3^a in the plunger head 3.

The operation is as follows: To raise the cover B, the lever P is moved to the right, thereby forcing the end of the lever F upwardly, and by engagement of said lever with the pin 3^a, the member 3 and contacts Q are brought into the position shown in Fig. 2. A further movement of levers P will raise the cover (through contact with said cover) with the free end of lever F, as in Fig. 1. The cover may then be opened sufficiently to make necessary repairs, etc., and may be closed by a reverse motion of lever P, and a continued movement of the lever in this reversed direction will close the contacts Q upon the contact Q'.

It is obvious from an observation of Fig. 4 that an attempt to close the cover B while the switch is in the "on" position would result in contacting the member N' with the abutment R and necessitate a reversal of the switch to the "off" position, before the closing of the cover would be effected. Similarly, from an inspection of Figs. 3 and 4, it is obvious that the cover could not be opened while the switch is closed; because of contact of the member N' with the abutment R.

What we claim and desire to secure by Letters Patent is:—

1. In an electric switch, a case, a cover on the case, a spring secured to said cover, slots in the ends of said spring, plates engaging the slots, a plunger head, said plunger head having grooves, said plates engaging said grooves, said plunger head having a pin, a bifurcated lever engaging said pin for actuating said plunger head against the action of said spring, means for actuating the lever, electric contacts secured to said case, and electric contacts carried by said plunger head adapted to engage the first said electric contacts.

2. In an electric switch, a case, a cover on the case, a spring secured to said cover, slots in the ends of said spring, plates engaging the slots, a plunger head, said plunger head having grooves, plates engaging said grooves, a bifurcated lever engaging said plunger head to actuate the same, a rod carried by said cover, a tube carried by said plunger head, said tube being slid-

able upon said rod for guiding said plunger head, stationary electric contacts in said case, and electric contacts carried by said plunger head adapted to engage said stationary electric contacts.

3. In an electric switch, a case, a cover on the case, a rod centrally secured to the cover, a plunger mechanism slideable upon the rod, electric contacts stationary within the case, electric contacts carried by the plunger mechanism adapted to engage the first said electric contacts, spring pressed members connecting with the plunger mechanism for accelerating the motion of said plunger mechanism, and means for moving said plunger mechanism against the spring pressure.

4. In an electric switch, a case, a cover on the case, a rod centrally secured to the cover, a plunger mechanism slideable upon the rod, electric contacts stationary within the case, electric contacts carried by the plunger mechanism adapted to engage the first said electric contacts, spring pressed members connecting with the plunger mechanism for accelerating the motion of said plunger mechanism, a lever in said case, a spindle carrying said lever, a second lever external to the case and mounted on said spindle for actuating the plunger mechanism.

5. In an electric switch, a case, a cover on the case, a rod centrally secured to the cover, a plunger mechanism slideable upon the rod, electric contacts stationary within the case, electric contacts carried by the plunger mechanism adapted to engage the first said electric contacts, spring pressed members connecting with the plunger mechanism for accelerating the motion of said plunger mechanism, a bifurcated lever engaging a pin in said plunger mechanism for actuating a said plunger mechanism, and means for actuating the lever.

In witness whereof we have hereunto set our hands in presence of two witnesses.
